CABINET OR THE LIKE

Warren C. Church, Hurt, Va., assignor to The Lane Company, Inc., Altavista, Va., a corporation of Virginia

Application February 17, 1959, Serial No. 54,647

Term of patent 14 years

(Cl. D33—19)

The essential features of the design are shown in the drawing in solid lines.

The back or rear of the cabinet or the like (not shown in the drawing) is plain and unornamented.

The left hand side of the cabinet or the like (not shown in the drawing) is plain and unornamented, and will be similar in appearance to the right hand side of the cabinet or the like, as is customary.

I claim:

The ornamental design for a cabinet or the like, as shown and described.
